United States Patent Office

Des. 221,993

Patented Sept. 21, 1971

221,993

PILECAP TEMPLATE

Robert J. Crawford, 7019 Altair Parkway,
Sacramento, Calif. 95823

Filed Feb. 9, 1970, Ser. No. 21,335

Term of patent 3½ years

Int. Cl. D10—99

U.S. Cl. D52—6

FIG. 1

FIG. 3

FIG. 2

FIG. 1 is a plan view of the obverse of a pilecap template claimed herein, the reverse plan view being a mirror image thereof;

FIG. 2 is an elevation of one side of said pilecap template, the elevation of the other side being similar; and

FIG. 3 is an elevation of one end of said pilecap template, the elevation of the other end being similar.

I claim:

The ornamental design for a pilecap template, as shown and described.
